MIXING APPARATUS.

1,075,524.

Specification of Letters Patent. Patented Oct. 14, 1913.

Application filed September 26, 1912. Serial No. 722,521.

To all whom it may concern:

Be it known that we, WILLIAM S. VEACO and THOMAS J. BENNETT, citizens of the United States, residing the said VEACO at 5 Berkeley, Alameda county, State of California, and the said BENNETT in the city and county of San Francisco, State of California, have invented certain new and useful Improvements in Mixing Apparatus, of which the following is a specification.

The hereinafter described invention relates to an improved power operated mixing apparatus particularly adapted for the mixing and agitating of liquids or for the 15 whipping of cream or the like, and has for its principal object to provide an apparatus of the above type in which the operating motor is stationarily mounted and the shaft supporting the agitator is capable of movement relative to its operating motor, that 20 the motor may be set in motion and the position of the agitator in the liquid may be adjusted to any desired level.

Another and important object is to provide 25 a mixing apparatus so constructed that the motor may be thrown into operation regardless of the position of the agitator relative to the fluid to be mixed, which is a decided advantage over the devices now 30 employed in which the starting of the motor and the rotation of the mixing blades is regulated by the lowering of the motor and the insertion of the mixing blades into the fluid to be agitated or mixed.

35 A further object is to provide a mixing apparatus which is constructed of few parts, is thoroughly efficient in its operation, and in which the operating motor is stationarily mounted relative to the supporting base.

40 The invention consists in an electrically operated motor stationarily mounted above a supporting base, a switch controlling the operation of said motor, a shaft mounted to slide vertically through the armature shaft 45 of said motor and adapted to be rotated thereby, a supporting bearing for said shaft, an agitator carried by said shaft, and means for sliding said shaft relative to said motor.

With these and other objects in view, the 50 invention consists in the construction and novel combination of parts hereinafter fully described, illustrated in the accompanying drawing, and pointed out in the claims here-to appended; it being understood that various changes in the form, proportion, size 55 and minor details of construction, within

the scope of the claims hereto appended, may be resorted to without departing from the spirit or sacrificing any advantages of the invention.

60

To comprehend the invention reference should be had to the accompanying drawing, wherein—

Figure 1 is a view in elevation of our improved apparatus, disclosing the base, the 65 standard supporting the motor, and the agitator carried by its supporting shaft submerged in the material to be mixed in full lines, and withdrawn therefrom in dotted lines. Fig. 2 is a vertical central sectional 70 view disclosing the shaft extending through the motor armature and constructed to slide therethrough, the supporting bearing for said motor, the agitator at the lower end thereof, the shaft being disclosed in full 75 lines withdrawn from the material to be mixed and in dotted lines submerged in the material.

Referring more particularly to the drawings, the reference numeral 1 designates a 80 suitable base through which extends, adjacent one edge thereof, the lower end of a tubular supporting standard 2 which is secured in position by the nuts 2' and 2''. Secured to the standard 2 adjacent its upper 85 end is a laterally extending arm 3 which supports at its outer end a casing 4 of an electrically operated motor constructed with a revolving armature 5 supported on a tubular shaft 5' insulated therefrom and said 90 shaft revolves on bearings 6 and 7 in the casing 4. The armature is rotated through electricity received by the brushes mounted in the casing and to which are connected the 95 ends of conducting wires 9 which are concealed within the arm 3 and extend downwardly in the center of the tubular standard 2, and the lower ends of the wires extending from under the base 1 through a cut out 3' and are connected to any suitable source of 100 electric energy. The flow of current through the armature is regulated by a switch 10 mounted to reciprocate in the upper end of the standard 2.

Slidably mounted within a suitable bore 105 11 in the armature shaft is a vertically extending cylindrical shaft 12, formed throughout its length with a key-way 13, in which extends a key 14 projecting from the interior surface of the bore 11. The upper end of the shaft 12 is rotatably mounted in a bearing 15, slidably mounted within 110

a guide tube 16 the lower end of which is screw threaded to the upper portion of the casing 4, the tube being closed at its upper end by a cap 16'. Encircling said guide tube is an adjusting sleeve 17 secured to the bearing 15 through the medium of a connecting screw 18, extending through a vertical slot 19, formed longitudinally of the guide tube 16. The adjusting sleeve 17 is provided on its interior surface with a spring pressed friction pawl 20, which is adapted to engage the surface of the tube 16 and retain the sleeve and parts carried thereby stationary thereon.

15 From the above description, it will be observed that by grasping the adjusting sleeve 17 and sliding the same upon the tube 16, the shaft 12 will be raised and lowered relative to the armature shaft, and that by 20 feathering the shaft 12 to the armature shaft the two shafts will be rotated by the armature.

Secured in any suitable manner to the lower end of the shaft 12 is an agitator formed of a plurality of spaced, inclined blades 21, radiating from a hub 22, and said blades revolve at a high rate of speed when the motor is operated and are adapted when submerged in the liquid contained 30 in a vessel 23 to thoroughly agitate and mix the same.

To properly position the vessel 23 relative to the agitator, a guide ring 24 is secured to the base 1 directly below the center of the shaft 12, and is adapted to receive the base 35 of the vessel.

It will be apparent that we have provided a mixing apparatus in which the shaft carrying the agitator is adjustable relative to 40 the motor and that it is not necessary to raise and lower the motor to insert the agitator in the material to be mixed and that it is not required to lower the agitator for any required distance in the material to be 45 mixed before the motor can be operated, but that the motor may be operated when the agitator is at any elevation.

Having thus described our invention what is claimed as new and is desired to be 50 protected by Letters Patent is—

1. In a mixing apparatus of the class described, the combination with a supporting standard, an electrically operated motor secured thereto and provided with a rotating 55 armature, a tubular shaft supporting said armature, electrical connections between said armature and a source of electric energy, a shaft adjustably mounted in said tubular armature shaft and adapted to rotate there- 60 with, an agitator secured to the lower end of said shaft, means for adjusting said shaft relative to said armature, and devices for retaining said shaft in its adjusted position.

2. In a mixing apparatus of the class described, the combination with a supporting 65 standard, an electrically operated motor secured thereto and provided with a rotating armature, a tubular shaft supporting said armature, electrical connections between said armature and a source of electric energy, a 70 shaft adjustably mounted in said tubular armature shaft and adapted to rotate there- with, an agitator secured to the lower end of said shaft, and means for adjusting said shaft relative to said armature. 75

3. In a mixing apparatus of the class described, the combination of a supporting standard, an electrically operated motor carried thereby and provided with a rotating armature, electrical connections between said armature and a source of electric energy, a switch for controlling the flow of current 80 into said armature, a tubular shaft supporting said armature, a shaft adjustably mounted within said tubular shaft and adapted to 85 rotate therewith, a guide tube extended upwardly from said motor and adapted to receive the upper end of said shaft, a bearing for said shaft adjustably mounted within said guide tube, means for adjusting said 90 last mentioned shaft relative to said tubular armature shaft, and an agitator mounted on the lower end of said adjustable shaft and adapted to rotate therewith.

4. In a mixing apparatus of the class 95 described, the combination of a tubular supporting standard, an electrically operated motor carried at the upper end thereof and provided with a rotating armature, electrical 100 connections between said armature and a source of electric energy and said connections extended within said tubular standard, a switch in said standard for controlling the flow of current into said armature, a tubular shaft supporting said armature, a 105 shaft adjustably mounted within said tubular shaft and adapted to rotate therewith, a guide tube extended upwardly from said motor and adapted to receive the upper end of said shaft, a bearing for said shaft adjustably mounted within said guide tube, means exteriorly of said guide tube and connected to said bearing for adjusting said 110 last mentioned shaft relative to said tubular armature shaft, and an agitator mounted on the lower end of said adjustable shaft and adapted to rotate therewith. 115

In testimony whereof we have signed our names to this specification in the presence of two subscribing witnesses.
